J. R. ROSE

BLOWPIPE

Filed Aug. 15, 1927

UNITED STATES PATENT OFFICE.

JAMES B. ROSE, OF PITTSBURGH, PENNSYLVANIA, ASSIGNOR TO TORCHPARTS GAS APPLIANCE COMPANY, OF CLEVELAND, OHIO, A CORPORATION OF DELAWARE.

BLOWPIPE.

Application filed August 15, 1927. Serial No. 212,895.

This invention relates to blowpipes, and more particularly to blowpipes that are used for the purpose of cutting metals with gases. It is the general object of the invention to 5 provide a blowpipe of this character which is efficient in operation and which is simple in construction and economical of production.

A further object of the invention is to provide for blowpipes of this character a tip 10 which can be made of copper and the parts of which are so constructed that it may be provided, at comparatively low cost, with drilled passages for the preheating gases. Other limited objects of the invention will appear 15 hereinafter in connection with the detailed description which will be made with reference to the accompanying drawing, wherein Fig. 1 represents a side elevation of a blowpipe constructed in accordance with my invention; Fig. 2 a plan view of the said blowpipe; Fig. 3 a central vertical sectional view through the said blowpipe; Figs. 4, 5, 6 and 7 are details in section corresponding respectively to the lines 4—4, 5—5, 6—6 and 7—7 25 of Fig. 3; and Fig. 8 a plan view of the tip.

The blowpipe shown herein comprises generally a head A and a tip B with a shouldered nut C connecting the tip and head.

Assuming that the blowpipe is used in the 30 position shown in Figs. 1 and 3 of the drawing and describing the parts by reference to such positions, the head A comprises a horizontal portion A' and a vertical portion A²; that is to say, the parts A' and A² are arranged as substantially right angles to each other. The part A' is provided with an upper 35 passage 1 for cutting oxygen, the oxygen being supplied to said passage by a tube 2. At its front end, the passage 1 communicates with a vertical passage 1^a arranged centrally within the part A² of the head. The lower end of the passage 1^a opens into a chamber within the lower portion A² of the head. This chamber is provided with a frusto-conical wall A³ 40 extending downwardly from the lower end of the passage 1^a, with a cylindrical wall A⁴, and a lower frusto-conical wall A⁵.

At its rear end, the part A of the head is widened and receives on opposite sides thereof 45 the tubes 3 and 4, the former pipe conducting preheating oxygen to the rear of the head and the latter pipe conducting combustible gas to the opposite side of the rear of the head. Mounted in a bore 5 in the lower portion of 55 the part A is an injector mixer, the said in-

jector mixer comprising a tubular body 6 having an angular head 7 at the rear thereof and a cylindrical surface 7^a in front of such angular portion, and a shoulder 7^b in front of the surface 7^a, the said shoulder being 60 adapted to engage the rear of the portion of the head surrounding the bore 5.

The injector body in front of the cylindrical part 7^a is reduced in diameter to provide with the bore 5 an annular chamber 8, 65 which annular chamber receives oxygen from a passage 9 which communicates with a shallow chamber 10 into which the tube 3 extends. The oxygen supplied to the chamber 8 is delivered to the bore 6^a of the injector through 70 radial ports 11.

In front of the said radial ports, the injector body is threaded into a correspondingly threaded portion of the bore 5; and in front of such threaded portion, the diameter of the 75 injector is reduced to provide a second annular chamber 12 which communicates with the bore of the injector by the radial ports 13. The chamber 12 receives combustible gas through a port 14 extending thereinto from 80 the shallow chamber 15 with which the pipe 4 communicates. The front or delivery end of the bore 6^a discharges into a chamber 5^a constituted by the front of the bore 5. From this chamber a passage 15^a delivers the preheat- 85 ing mixture into the head chamber D below the wall A³.

Cooperating with the head just described is the tip, indicated generally at B. This tip comprises an outer member 16, an inner 90 member 17, and a head member 18.

The inner member is provided at its upper end with a thread 19 by which it is secured in place within the head 18, the upper end of said inner member being rounded, as 95 shown at 17^a and fitting against a concave seat 18^a formed within the head. The inner member has a bore 20 which registers with the bore 21 of the head. Beneath the threaded portion 19, the inner tip member has opposite sides faced off, as shown at 17^b, thereby providing vertical passages between these portions and the surrounding outer tip member, which passages communicate at their upper ends with the chamber formed within the sleeve 18^b of the head 18. Below the portions 17^b, the member 17 is reduced in external diameter, as shown at 17^c, providing with the surrounding outer tip member an annular distributing chamber D from which 100 110

the mixture is delivered through inclined passages 21^a to the operating end of the tip.

These passages are conveniently formed by milling slots into the enlarged tapered end 5 of the inner member, the correspondingly tapered portion 16^a of the outer member engaging the tapered portion of the inner member and thus converting the slots into passages.

10 The upper end of the outer member 16 is threaded into the bottom of the head 18. The operation of threading this member into the head causes its tapered lower end to be drawn into close engagement with the tapered lower 15 end of the inner member.

The head 18 has the cylindrical sleeve 18^b at its lower end, a short cylindrical portion 18^c thereabove, of greater diameter than the portion 18^b, and an upper cylindrical portion 18^d of smaller diameter than either the parts 18^b or 18^c. The part 18^c is provided at its upper edge with a tapered or frusto-conical surface 18^e adapted to engage the frusto-conical seat formed by the wall A⁵; 25 and the upper cylindrical part 18^d is provided with a frusto-conical portion 18^f adapted to engage the frusto-conical seat formed by the wall A³. The shouldered nut C, hereinbefore referred to, serves to secure the tip 30 to the head, said nut being threaded upon the lower threaded end of the head with its shoulder engaging the cylindrical projection 18^c. When the nut is set up, it forces the tapered surfaces on the head 18 into engagement 35 with the tapered seats A³ and A⁵ within the blowpipe head, thus forming a tight and leak-proof joint.

The preheating mixture delivered through the passage 15 into the chamber D provided 40 above the part 18^c of the head is supplied to the vertical passages E by means of short ports 22 drilled through the portion of the head defined by the part 18^c and so much of the part 18^b as extends to the chamber formed 45 in the bottom of the head for the reception of the outer tip member.

With the parts constructed and arranged as described, the operation will be easily understood. Oxygen supplied through the 50 tube 3 and combustible gas supplied through the tube 4 are delivered to the injector, the oxygen entering through the ports 11 and the combustible gas through the ports 13. The oxygen entering the bore of the injector exercises an aspirating effect upon the gas supplied through the ports 13 and the gases are mixed to some extent in the forward end of the bore of the injector, as well as in the chamber 5^a, in the ports 15, and in the chamber D, as well as in their transit to the operating 60 end of the torch. When the metal shall have been preheated by the preheating flames, cutting oxygen is turned on through the tube 2 and, passing downwardly through the passage 1^a and the bores 21 and 20, will

serve to cut the metal in a well-known manner.

It is desirable that the tip should be formed of copper; and all three parts of the tip shown herein are made of that metal. It 70 is also desirable that the drilled ports 22 shall be as short as possible, in order to minimize the difficulty and expense attending the drilling of long passages. This result is secured by the construction of the head. 75

The blowpipe described herein is extremely simple of construction and economical of production, but is, however, markedly efficient in operation.

Having thus described my invention, what I claim is:

1. A blowpipe tip comprising a head having a reduced upper portion provided at the upper end thereof with a frusto-conical seating surface, said head also having a portion of greater diameter below the first mentioned portion, the second portion having at its upper end a tapered or frusto-conical seating surface, the said head being provided with a reduced cylindrical portion extending 85 downwardly from the second portion and having an internally threaded chamber in the bottom thereof and a central bore extending upwardly through the said head from the said chamber, the lower portion of the said bore being threaded, an inner tip member having a central bore and threaded into the bore in said head, and an outer tip member threaded into the chamber provided in said head, there being passages provided between 90 the inner and outer tip members for preheating gases and there being passages extending 95 upwardly from the chamber in the said head through the second enlarged portion thereof and adapted to receive a preheating mixture. 105

2. A blowpipe tip comprising a head having a chamber in the lower end thereof and a central bore extending upwardly therefrom through from said chamber, the lower portion of the said bore being threaded, an inner tip member threaded in said bore and itself having a bore therethrough registering with the upper portion of the bore in said head, an outer tip member threaded into the lower portion of the said chamber and forming 110 passages for preheating gases with the inner tip member, the said head having vertically or longitudinally extending passages therein extending from the chamber provided in the lower portion of said head through 115 a portion of the said head intermediate the top of said chamber and the top of the head. 120

3. A blowpipe tip comprising a head having a reduced upper portion and a large intermediate portion and a smaller depending portion, the last mentioned portion of the head being provided with a chamber projecting upwardly thereinto, the said chamber being internally threaded, the head having a bore extending therethrough from said cham-

ber and the lower portion of the bore being enlarged and threaded, an inner tip member threaded into the lower portion of the said bore and having a bore adapted to register with the upper portion of the bore in said head, an outer tip member threaded into the bottom of the chamber in said head and providing, with the inner member, passages for a preheating mixture communicating at their upper ends with the said chamber, the 10 said head having one or more passages extending upwardly from the chamber therein through the top of the second portion thereof.

In testimony whereof, I hereunto affix my signature.

JAMES R. ROSE.
